UNITED STATES PATENT OFFICE.

WILLIAM JOHN ELDER, OF OSWEGO, NEW YORK.

FEED MECHANISM FOR WOOD-REWORKING MACHINES.

1,378,845.

Specification of Letters Patent. Patented May 24, 1921.

Application filed June 21, 1918, Serial No. 241,114. Renewed October 29, 1920. Serial No. 420,579.

To all whom it may concern:

Be it known that I, WILLIAM JOHN ELDER, a citizen of the United States, and resident of the city and county of Oswego and State 5 of New York, have invented certain new and useful Improvements in Feed Mechanisms for Wood-Reworking Machines, of which the following is a specification.

This invention relates to feeding mechanism 10 for wood reworking machines; and especially to mechanism whereby squared timber lengths are delivered to the usual vertical feed rolls of a resawing or other cutting instrumentality.

15 The object of my invention is to provide an automatic mechanism of simple and efficient construction whereby timber lengths are removed from a suitable source of supply, properly positioned, and fed in endwise succession to the resawing or other cutting mechanism; thereby effecting labor economy, reducing liability of injury to the operator, and insuring increased output.

The invention, generally stated, comprises 25 a support upon which squared timber lengths are stacked; a conveyer whereby the lowermost lengths are successively removed from the stack and advanced in endwise relation to each other, and means whereby 30 said lengths are successively disposed on their lower longitudinal edges, in vertical position, preparatory to their delivery to the resawing or cutting machine.

The invention also comprises various novel 35 features of construction and combinations of parts which will be hereinafter described and claimed.

In the drawings—

Figure 1 is a perspective view of timber 40 feeding mechanism embodying the principle of my invention, showing a piece of timber as positioned within the guide structure.

Fig. 2 is a plan view of the apparatus, showing its relation to the feed roll mechanism of a wood reworking machine.

Fig. 2^a is a partial sectional elevation of the feed-rolls and adjuncts of the reworking machine, as on the line 2^a—2^a of Fig. 2.

Fig. 3 is a side elevation of the apparatus. 50 Fig. 4 is an elevation of the right-hand or feeding end of the apparatus shown in Fig. 3.

Fig. 5 is a transverse vertical section of the apparatus on a plane through the delivery end of the inclined feed table and adjuncts, as on the line 5—5 of Fig. 3.

Fig. 6 is a similar section through the vertical guiding structure and adjuncts, as on the line 6—6 of Fig. 3.

Fig. 7 is a partial section through said 60 structure adjacent the screw adjusting devices therefor, as on the line 7—7 of Fig. 3.

Fig. 8 is a similar section on a plane through the flexible deflecting strips, as on the line 8—8 of Fig. 3, showing the timber 65 as positioned vertically thereby.

Referring to the drawings, 10 designates a substantial frame work including two spaced cross bars 11 having outwardly and upwardly inclined end extensions 12 in 70 parallelism with each other. Supported on these extensions are two longitudinal beams 13 one of which is arranged at the lower and the other at the upper ends of the extensions. On the outer or higher beam are 75 secured the angular supporting ends 14 of cross-straps 15 which incline downwardly toward the inner or lower beam and sustain an inclined table 16 which is adapted to receive and support a stack of squared timber 80 lengths to be operated upon. The lower ends of the cross-straps have upstanding portions 17 which are affixed to an upwardly and outwardly inclined wall 18 at the lower end of the table, which wall in 85 turn is borne by stout standards 19 on the main frame and is adapted to support and guide the lower edges of the material stacked on the table. The successive lowermost lengths are individually advanced in inclined position from the stack, as herein-after described.

On the inner face of the wall 18, adjacent to the delivery end of the table, is a flanged bar 20, which is mounted for adjustment 95 longitudinally of the wall. In the present instance the basal flange of the bar is provided with screw-bolts 21 which extend through spaced longitudinal slots 22 in the wall and are provided at their upper ends 100 with clamp nuts 23, whereby the bar may be secured to the wall in any predetermined position of adjustment longitudinally of the latter, as the length of material to be operated upon may require. Mounted on the bar 20 is a guide plate 24 which terminates short of the table so as to provide a throat through which the lowermost timber length may be withdrawn from the stack, the body of the plate constituting a positive stop for 110 the contiguous ends of the remaining material. The plate 24 is adjustable toward and

from the table according to the thickness of the timber. For this purpose the plate is provided with screw-threaded studs 25 which extend through spaced slots 26 in the bar and bear exterior clamp-nuts 27.

Suitably arranged on the beams 13 are two pairs of bearing brackets 28 in which are journaled the respective shafts 29 of a chain conveyer comprising two spaced 10 chains 30 which are carried by sprocket wheels 31 fast on the respective shafts 29; said chains being connected at spaced intervals by means of cross-bars 32 which extend beyond the outer faces of the chains. The 15 upper runs of the chains travel in longitudinal marginal recesses 33 in the top of the table 16 and the cross-bars of such run extend across and travel upon the surface of the table so as to take against the opposing 20 ends of the succeeding lowermost timbers of the stack and advance them therefrom along the table, as will presently appear.

The conveyer may be driven through any 25 suitable transmitting mechanism from a primary source of power. In the present instance the outer shaft 29, adjacent its lower end, is provided with a sprocket wheel 34 which is connected by means of a chain 35 with a similar wheel 36 on a horizontal shaft 30 37 having its bearings in boxes on the main frame adjacent the delivery end of the chain conveyer. The shaft 37 bears a pulley 38 which is connected by means of a belt 39 with a pulley 40 on a driven shaft 41 35 having its bearings in brackets on that end of the main frame adjacent the resawing machine. Thus the power is transmitted from the shaft 41 to the shaft 37, thence through the sprocket gearing described to 40 the chain conveyer. The pulleys 38, 40 are preferably of the speed or cone type, whereby variable speed may be transmitted to the conveyer as desired.

As each of the lowermost timbers is advanced in inclined position from the stack by the chain conveyer the leading end of the lower side of the timber is acted upon by positioning devices hereinafter described which tend gradually to swing the inclined 45 material vertically on its lower longitudinal edge. The timber thus positioned progresses through a longitudinal guide structure leading to the vertical feed rolls 42 of the resawing or cutting machine, which 50 feed rolls are mounted for adjustment toward and from each other in any usual or approved manner in order to adapt them to the feeding of material of different thicknesses. In the present instance I have selected for illustration a construction in 55 which the shafts 43 of the feed-rolls have their bearings in slidably-mounted carriage members 44 which carry the horizontally-adjustable timber guides 45 in advance of 60 the rolls. On the lower ends of the shafts 65

43 are bevel gear wheels 46 in mesh with similar wheels 47 slidably splined on an underlying shaft 48 which is supported in the frame of the resawing machine and is driven from a suitable source of power. 70 (See Figs. 2, 2^a and 3.) Thus the feed rolls are simultaneously actuated. The carriage members are provided with internally-threaded portions 49 which receive the right and left hand threaded portions respectively 75 of a hand operated shaft 50, by the manipulation of which the carriage members, together with their appurtenances, may be moved toward or from each other as desired. The feed-roll mounting and the adjusting 80 devices therefor, being old, require no detailed illustration or description.

In the present instance the shaft 41 is driven from the power-actuated shaft 48 of the resawing machine through a sprocket 85 chain 51 which passes about a wheel 52 on the shaft 48 and about a wheel 53 which is mounted on a stud shaft 54 extending from a bracket on one of the longitudinal beams 55 of the main frame. The lower run of 90 the chain 51 in its passage between the wheels 52, 53 meshes with a sprocket wheel 56 on the shaft 41 and thereby transmits the motion to the latter shaft from the shaft 48.

The guide structure above referred to 95 comprises a longitudinally-disposed bed 57 supported by brackets 58 on the beams 55 of the main frame, and two spaced parallel walls 59, 60 which are arranged on the bed so as to extend lengthwise thereof and provide a guide and support for the edgewise disposed material in its passage to the feed-rolls. The inner end of the wall 59 extends near to the delivery end of the inclined table 16, and the corresponding end of the other wall 60 terminates some distance short of the conveyer to provide sufficient space for certain timber positioning devices below described. The guide walls 59, 60 are adjustable toward and from each other so 105 as to vary the distance therebetween correspondingly with the space between the feed-rolls 42 of the wood reworking machine.

In the present instance the ends of the 110 guide walls adjacent the feed rolls, are hinged, as at 61, to the adjustable guides 45, whereby when the carriage members are adjusted to vary the space between the feed rolls the hinged ends of the guide walls 115 59, 60 are correspondingly adjusted. Means are provided whereby the bodies of the guide walls may be swung apart or toward each other according to the extent of adjustment of their delivery ends, in order to 120 insure the parallelism of the walls. Such means in the form illustrated comprises a shaft 62 having right and left hand screw threads thereon, which shaft is supported in 125 a transverse bearing bracket 63 on the un- 130

derside of the bed 57 (see Figs. 1, 2 and 7). Brackets 64 pivoted to and depending from the respective side walls 59, 60 have internally-threaded portions which receive the 5 respective screw-threads of the shaft. This shaft is preferably provided at one end with a hand-wheel 65 to facilitate the operation of the shaft for the relative bodily adjustment of the guide walls.

10 On the bed 57, throughout the greater part of its length, is the upper run of a belt conveyer 66 which passes about pulleys 67, 68 at the respective ends of said bed. One (67) of these pulleys is fast on the driven 15 shaft 41 and the other (68) on a shaft 69, having its bearings in brackets on the frame beams 55, whereby during the operation of the machine the upper run of the belt conveyer travels toward the resawing machine 20 and thus feeds endwise to the latter the material supported edgewise within the guide structure. I preferably provide for the belt conveyer a tension roll 70 carried by a suitably-disposed weighted lever 71 having a 25 yoke portion 72 which is loosely hung from the shaft 41. (See Figs. 2, 3 and 6.) This conveyer is run somewhat faster than the spaced feed rolls 42 of the resawing machine in order that the succeeding pieces of material 30 within the guide structure shall be maintained in end to end contact with each other. If a positive conveyer be employed it should be provided with an ordinary friction drive to allow for slippage during the 35 feeding operation.

Supported on the bed 57, adjacent to the lateral opening of the guide wall 60, is a supporting wall 73 which is arranged at the same angle of inclination as the upper runs 40 of the chain conveyer, or substantially so. Affixed to the inner face of this inclined wall, at the end thereof adjacent the chain conveyer, are two spaced strips 74, 75 of spring metal, which are curved gradually 45 upward and inward so as to extend through the wall opening and overhang the belt conveyer 66, the outer strip 75 rising somewhat higher than the other, as clearly shown in Figs. 1 and 8. To the inner end of the wall 50 60 of the longitudinal guide structure is affixed one end of a relatively broad spring strip 76 which curves over upon the inner face of the inclined wall 73 and is slightly twisted toward its free end in order to prevent a cam-like surface adjacent to the lower 55 portions of the strips 74, 75. Secured to the inner end of the other wall 59 of the guide structure is a curved plate 77 which overlies and rests upon the timber supporting wall 18.

The relative arrangement of the strips and plate just described is such that as each lowermost timber is advanced in inclined position from the stack by the chain conveyer the leading end of the timber is di-

rected into the receiving end of the guide structure, and after the timber escapes the stop plate 24 of the wall 18, such leading end is pushed forcibly against the opposing strip 74 which, yielding, acts against the 70 side of the timber about the middle thereof. This strip by its inherent elasticity thus swings with a lifting force the timber toward the vertical, (as indicated in Fig. 8) and as the material progresses the upper lateral portion thereof contacts with the longer strip 75 which thereupon acts to complete the movement of the timber to a vertical position; the lowermost strip 76 serving as a 75 guide and support for the leading end of the timber as the latter approaches and assumes its upright position. As the timber is thus being caused to assume a vertical position, the curved end plate 77 guides and supports the rear end of the material. The 80 timber thus positioned on its lower edge is transported by the belt conveyer to the feed-rolls of the resawing or cutting machine as previously described.

While I have herein described a construction whereby single timber lengths are successively advanced from the stack by the chain conveyer, it is to be understood that two or more lengths may be successively advanced thereby and the same positioned 90 within and fed along the guide structure similarly to a single length. It is also to be understood that my invention is not limited to the specific features of construction herein disclosed, as the same may be 95 modified within the principle of my invention and the scope of the appended claims.

I claim—

1. In feed mechanism for wood reworking machines, the combination of means 105 for supporting a stack of timber lengths, means for removing the lengths successively from the stack, a spring pressure element arranged in the path of the succeeding progressing lengths and constructed to exert 110 a lateral lifting pressure thereagainst and thus dispose them vertically on their lower longitudinal edges, and means for delivering such lengths thus positioned to the reworking machine.

2. In feed mechanism for wood reworking machines, the combination of means for supporting a stack of timber lengths, means for removing the lengths successively from the stack, a spring pressure element arranged in the path of the succeeding progressing lengths and constructed to exert 120 a lateral lifting pressure thereagainst and thus dispose them vertically on their lower longitudinal edges, a guide structure for the thus positioned lengths, and means for advancing such lengths end to end through the said structure.

3. In feed mechanism for wood reworking machines, the combination of means for 130

supporting a stack of timber lengths, means for advancing the lengths successively from the stack, a series of spaced spring strips curved gradually upward and inward so as to extend successively into the path of the progressing lengths and thus exert lateral lifting pressure against said lengths and dispose them vertically on their lower longitudinal edges, and means for delivering such lengths thus positioned to the reworking machine.

4. In feed mechanism for wood reworking machines, the combination of means for supporting in inclined position a stack of timber lengths, means for advancing the lengths successively from the stack in inclined position, a series of spring members extending successively into the path of the advancing inclined lengths and positioned to bear laterally against such lengths and swing them vertically on their lower longitudinal edges, a guide structure for the thus vertically positioned lengths, and means for advancing such lengths along said structure.

5. The combination with a wood reworking machine having spaced parallel feed rolls, carriage members therefor, and means for adjusting said members to vary the space between the rolls, of means for supporting a stack of timber lengths, means for removing the lengths successively from the stack, means for engaging the succeeding lengths as they progress and disposing them vertically on their lower longitudinal edges, a guide structure, and means for advancing such lengths end to end through the said structure to the said feed rolls, said structure including side walls flexibly connected to and adjustable with the respective carriage members, and means remote from said members for adjusting said walls and insuring their spaced parallel relation to each other.

45 6. The combination with a wood reworking machine having spaced parallel feed-

rolls, carriage members therefor, and means for adjusting said members to vary the space between the rolls, of a support remote from said rolls adapted to receive a stack of timber lengths, means for advancing the lengths successively from said support, a series of spaced spring strips curved gradually upward and inward so as to extend successively into the path of the progressing lengths and thus exert lateral lifting pressure against said lengths and dispose them vertically on their lower longitudinal edges, a guide structure, including adjustable side walls, for the thus vertically positioned lengths, means for adjusting said walls relatively to each other correspondingly with the feed rolls, and a conveyer for advancing such positioned lengths end to end through the said structure to the said rolls.

7. The combination with a wood reworking machine having spaced parallel feed rolls, carriage members therefor, and means for adjusting said members to vary the space between the rolls, of a support remote from said rolls adapted to receive a stack of timber lengths, means for advancing the lengths successively from said support, means for laterally engaging the progressing lengths and disposing them vertically on their lower longitudinal edges, a guide structure for the thus vertically positioned lengths, and means for advancing such lengths end to end through the said structure to the said feed rolls, said structure including side walls flexibly connected to and adjustable with the respective carriage members, and means remote from said members for adjusting said walls and insuring their spaced parallel relation to each other.

Signed at the city and county of Oswego and State of New York this 15th day of June, A. D. 1918.

WILLIAM JOHN ELDER.
